DRAWING APPARATUS FOR TEXTILE SPINNING AND LIKE TEXTILE FRAMES

Arthur Walker, Oldham, England

Application May 8, 1943, Serial No. 486,144
In Great Britain March 16, 1942

1 Claim. (Cl. 19—131)

This invention relates to drawing apparatus as employed in spinning frames, roving frames and other like textile frames for the treatment of fibrous material, and of the type commonly known as "high-draft," in which narrow bands, usually of leather, and running around a guide rail or nose-bar are employed as conveyors for roving or the like in the roller stand.

In known constructions, the bands, which are endless, are passed around the second bottom roller of the usual series of top and bottom rollers, for example, three pairs of rollers, and over a guide-rail or nose-bar, so that roving or the like passed between the sets of top and bottom rollers may be guided from the second pair of rollers to the nip of the front or first pair of rollers. The top rollers are usually weighted. The middle bottom roller is usually formed with a serrated surface but may have any other suitable frictional driving surface and is a driving roller for driving the endless bands, which for convenience will hereinafter be referred to as aprons.

The aforesaid driving roller usually extends in one length from end to end of a spinning or like frame and accommodates a more or less large number of endless aprons according to the number of spindles in the frame. The endless aprons need to be strung on to the driving roller from the ends of said roller when it is lifted out of the frame, as it is a matter of difficulty to joint the two ends of a band around the driving roller to form an endless band with the degree of accuracy essential. The endless aprons are slid along the driving roller into their respective operative positions. Should an apron break or develop a fault necessitating its removal from the driving roller, it is requisite to stop the machine, unweight the rollers and remove the driving roller to permit a fresh apron to be strung on said driving roller. It is therefore easily understood that the replacement on a driving roller of damaged aprons by fresh aprons is an irksome job entailing considerable loss of production, as the whole of one side of the frame may require to be stopped to permit replacement of one damaged apron. As a measure of alleviation it is sometimes the practice to string a few spare aprons on the driving shaft to obviate necessity for partially dismantling the frame, but this is only a palliative, as it is still necessary to stop all the spindles on one side of the frame and thus interfere with production while the fresh apron is being placed in position, unless the spare apron happens to be

in such a position that only a few spindles need to be stopped. In some apron systems it is possible to piece an apron around the driving roller, necessitating stoppage of two spindles only for the length of time it takes for the piecing to set. This method, however, does not ensure accurate piecing to be obtained, as the operation of piecing may sometimes be performed by unskilled or semi-skilled labour.

10 This invention overcomes all the disadvantages mentioned in a novel manner whereby any apron developing a defect may easily be removed from the machine and replaced by a fresh one without disturbance of the others or stoppage of the frame and therefore without undesirable interference with production.

A further advantage is obtained in the accurate guidance of the aprons in their paths of movement which may extend close to the nip 20 of the front top and bottom rollers.

According to the invention the endless aprons, instead of being strung upon the second bottom driving roller as previously described, are strung, preferably in pairs, on aligned rollers which are 25 only long enough to accommodate two aprons. Said rollers, hereinafter for convenience referred to as apron rollers, are journaled in cap bars intermediately of the second top roller and the second bottom roller, the latter of which is journaled lower than heretofore to permit the apron rollers to be mounted in intermediate position, between the top and bottom rollers. Said second bottom roller may, as before, be formed with a serrated surface or may have any other 30 suitable frictional driving surface and remains 35 the driving roller.

The endless aprons, of which there are two to each apron roller, are strung on said roller and trained around a stationary bar, preferably 40 of two spindles length, placed loosely in the nip of the front top and bottom rollers. Guiding means for the endless aprons may be provided on the stationary bar or elsewhere. The upper and lower flights of each apron extending directly 45 from the guide bar to the apron roller, and the upper flight of each apron serves exclusively to convey the fibers from the apron roller to the stationary bar.

50 The aprons passing around the apron rollers and between said rollers and the second bottom roller are driven by frictional contact with said second bottom roller.

The apron rollers may each have a plain, fluted or knurled surface or may be covered with leather 55 or have any other frictional driving surface, for

example, cork, and may be formed with rims or flanges to position the aprons, and are also weighted.

Should an apron develop a defect, it may be removed by taking off the weight from the rollers of the particular unit with which the apron is associated, lifting the top roller out of the cap bars and then lifting the respective apron roller from its bearings, and also the front stationary bar, whereupon the defective apron may be replaced by a fresh one and the rollers and guide bar replaced in position.

The said operation may be effected while the frame is working, the only section of the frame that is stopped being the two spindles associated with the two aprons on the apron roller which has been removed, thereby reducing interference with production to a minimum.

Some illustrative embodiments of the invention will now be described with reference to the accompanying drawing in which the same reference characters indicate corresponding parts in the several figures.

Fig. 1 is a side elevation, partly sectional, of a three-line roller arrangement of the high-draft type constructed according to one form of the invention; Fig. 2 is a front view of an apron roller, aprons, and apron guides shown separate from the roller stand; Fig. 3 is an end view of the guide shown in Fig. 2. Fig. 4 is a similar view to Fig. 2 of a modified form of apron roller and guide.

Referring to Fig. 1, 10 is a roller stand of the so-called pillar type mounted on the cross-rail 11 of a spinning frame; 12 is the front top roller; 13 is the second top roller and 14 the back top roller, each journaled in cap bars, one of which is shown at 15 pivotally mounted in the cap bar bracket 16 carried by the roller stand 10 and adjustable thereon; 17 is the front bottom roller; 18 the second bottom roller; 19 is the back bottom roller; 20 is the front top clearer and 21 the front under clearer. The front top roller 12 is weighted in known manner; 22 indicating a weight and 23 one of the hooks by which said weight is suspended from the front top roller 12.

The described arrangement is generally of known form except that the second bottom roller 18 journaled in an adjustable bearing 24 mounted in the roller stand is disposed in a lower position than heretofore.

This lower position permits the mounting of an apron roller 25 intermediate the second top roller 13 and the second bottom roller 18. The apron roller 25 is journaled in the cap bars 15 below and in parallelism with the second top roller 13. The axis of the apron roller 25 is located rearwardly of a plane extending through the axes of the second top roller 13 and the second bottom roller 18.

In the construction shown in Figs. 1 and 2 the apron roller 25 is formed of two spindles length, as shown in Fig. 2, and has two parts 25a, 25b of larger diameter spaced on opposite sides of a part 25c of smaller diameter, the spacing of the parts 25a, 25b being dependent on the spacing of the spindles with which the apparatus is to be used. A pair of endless aprons 26 is strung on the apron roller, one around each part 25a, 25b, said aprons also being trained around a stationary guide bar 27 placed loosely in the cap bars 15 with its forward edge close to the nip of the front top and bottom rollers, 12 and 17, respectively.

The guide bar 27 is furnished with pins 28 projecting from its underside, one on either side of each apron, see Fig. 2, which serve to guide the apron in its appointed path of movement.

Alternatively, each apron roller 25 may be formed with rims or flanges 25d, see Fig. 5, to position the respective aprons 26.

The aprons 26 passing around the apron roller 25 and between said roller and the second bottom roller 18 are driven by contact with said second bottom roller; each apron bearing on more than one-half of the periphery of the apron roller.

A presser roller 29 loosely mounted in the cap bars 15 and pressing on the aprons 26 serves to guide the roving or the like between the nip of the rollers 12 and 17.

The parts 25a, 25b of the apron roller 25 may be superficially plain, fluted or knurled, or may 20 be surfaced with leather or other frictional driving medium. For example, cork is found to provide a very effective surface.

In the apparatus shown in Fig. 1 weighting is applied to the apron roller 25 through the medium of a saddle 23a forming an extension of the weighting hook 23, said weighting serving to keep the apron roller in correct tension.

Should an apron 25 develop a defect, it may be removed by taking off the weight from the 30 particular unit with which the apron is associated, lifting the second top roller 13 out of the cap bars 15, then lifting the apron roller 25 from its bearings, and also the front stationary bar 27, whereupon the defective apron may be replaced by a fresh one and the rollers 25, 13 and guide bar 27 replaced in position.

The removal of said apron roller may be effected while the frame is working, the only section of the frame that is stopped being the 40 two spindles associated with the two aprons on the apron roller which has been removed.

It will therefore be seen that there is only a minimum of interference with production instead of the wholesale interference usually associated with change of an apron.

An advantageous feature of the present invention is the absence of cradles, tension devices and other features which are undesirable from the point of view of cleanliness as they afford surfaces for the accumulation of fly but are yet necessary to enable the systems with which they are used to work.

It is well-known that operatives have an objection to working systems which are complicated 55 with the above mentioned parts, and as the present invention dispenses with such parts it will be seen that the work of an operative will be facilitated.

What is claimed is:

Drawing apparatus of the "high-draft" type for textile spinning and like frames comprising roller stands, cap-brackets carried by said stands, cap bars pivotally mounted in said brackets, a first, second and third top roller and weighted 60 apron rollers journaled in said cap bars, a first, second and third bottom roller journaled in parallelism with said top rollers, a stationary guide-bar placed loosely in said cap bars with its forward edge close to the nip of the first 65 top roller and the first bottom roller, said apron rollers being journaled intermediately of said second top roller and said second bottom roller, the axes of said apron rollers being located rearwardly of a plane extending through the axes of 70 said second top roller and said second bottom 75 roller.

roller, said apron rollers comprising aligned roller members each of short length, two aprons trained around each apron roller member and said guide bar, said aprons being driven by frictional contact by their outer sides with said second bottom roller, said aprons bearing on said apron rollers over more than one-half of their peripheries, both flights of each apron extend-

ing directly from said guide bar to the respective apron roller member, the upper flights of said aprons serving exclusively to convey fibres to the nip of said front top and bottom rollers, each apron roller member being removable without stoppage of the frame or disturbance of adjoining roller members.

ARTHUR WALKER.
